UNITED STATES PATENT OFFICE.

JOHN F. SOUTHER, OF ARLINGTON, MASSACHUSETTS.

ICE-MAKING MACHINE.

1,127,104.

Specification of Letters Patent.

Patented Feb. 2, 1915.

Application filed February 16, 1914. Serial No. 818,851.

To all whom it may concern:

Be it known that I, JOHN F. SOUTHER, a citizen of the United States, residing at Arlington, in the county of Middlesex and 5 State of Massachusetts, have invented new and useful Improvements in Ice-Making Machines, of which the following is a specification.

This invention relates to machines for 10 making ice, the same being particularly adapted for use by private individuals so that they may during the cold season prepare sufficient ice for their own consumption for the whole year, the ice thus prepared being stored in a suitably constructed 15 ice house of sufficient size to hold a year's supply.

The object of the invention is to provide 20 a simple and easily operated machine for the purpose specified in which there is provided a primary receptacle or receptacles into which the water is poured and after 25 said water has been frozen in the primary receptacles, the ice thus formed is subjected to the freezing operation for another period of time in secondary receptacles contained in the machine of this invention, said secondary receptacles being adapted to receive the ice from the primary receptacles. It 30 has been found that where only one receptacle or set of receptacles is provided considerable time is required to freeze the water into a solid cake of ice and, therefore, it is desirable to first partly freeze the water 35 into cakes of ice and then empty the partly frozen contents of the first receptacles into a second set of receptacles wherein the freezing operation can be continued while the first set of receptacles are filled with water 40 to obtain a partial freezing of other cakes of ice. The cakes of ice will be thus frozen solid with a great saving of time and consequent increase in the efficiency and speed of the machine.

45 The invention consists in the combination and arrangement of parts set forth in the following specification and particularly pointed out in the claims thereof.

Referring to the drawings: Figure 1 is a 50 plan view of my improved ice making machine. Fig. 2 is a rear elevation of the same. Fig. 3 is a side elevation as viewed from the right of Fig. 2.

Like numerals refer to like parts throughout the several views of the drawings.

In the drawings, 5 and 6 are side frames

rigidly joined together by a base 7. In the upper part of the machine is a series of primary receptacles 8 rigidly fastened together. The receptacles at the opposite ends of said series are provided with trunnions 9 and 10, respectively, which have bearings in the frames 5 and 6. The trunnion 9 is extended to receive a gear 11 which is fast thereto. Said trunnion 9 also has a handle 12 fastened thereto whereby the same, together with the receptacles 8, may be rotated. The gear 11 meshes into a pinion 13 rotatably mounted on a stud 14 fast to the frame 5. The gear 13 meshes into a pinion 15 which is loosely mounted on a trunnion 16 fast to one of the end receptacles of a series of receptacles 17. The receptacle 17 at the opposite end of said series is also provided with a trunnion 18 journaled to rotate in bearings in the side frame 6.

The pinion 15 has a pawl 19 pivoted thereto which engages a ratchet 20 fast to the trunnion 16, whereby the pinion 13 and gear 11 may be rotated while the receptacles 17 are held stationary.

It will be noted that each of the receptacles 17 is provided with two oppositely disposed chambers 21 and 22 and that said receptacles are locked in position by means of a suitable hook 23 pivotally mounted on the side frame 5 of the machine. The receptacles 8 are also locked against rotation by means of a suitable hook 24 pivoted to the end receptacle 8 and engaging a pin 25 on the side frame 5.

Beneath the receptacles 17 an inclined platform 26 is provided upon which the ice is dumped when the receptacles 17 are rotated. It will be noted that the receptacles 8 are frustum-shaped and that they communicate one with the other by means of the passages 27.

The general operation of the mechanism hereinbefore specifically described is as follows: Assuming the parts to be in the position illustrated in the drawings, the primary receptacles 8 are filled with water. After the water has become frozen into cakes of ice, although not frozen solid to the center, 100 the operator unlocks the primary receptacles 8 and secondary receptacles 17 by unlocking the hooks 23 and 24 and then rotates the primary receptacles by means of the handle 12. This rotation will cause the pinions 13 and 15 to be rotated and consequently the trunnions 16 and 18, together with the secondary

receptacles fast thereto, will be rotated and the gear 11 being of twice the diameter of the pinion 15, a quarter rotation of said gear 11 will cause the gear 15 to make a half rotation. When the gear 11, together with the receptacles 8, has made a quarter rotation, the ice will slide out of the receptacles 8 and into the uppermost chamber 21 of the receptacle 17. The operator then hooks the 10 receptacle 17 in position by means of the hook 23 and reverses the direction of motion of the handle 12 and the receptacles 8 to bring them back to the position illustrated in the figures of the drawings ready 15 to be filled again with water for the manufacture of another set of cakes of ice.

During this backward rotation of the receptacles 8 the pawl 19 will slip over the teeth of the ratchet 20 without rotating the 20 same, thus leaving the receptacles 17 stationary while the receptacles 8 are being moved back to their original position. Water is then placed in the receptacles 8 again and the freezing operation takes place, both with 25 reference to the contents of the receptacles 8 and the contents of the receptacles 17. At the next partial rotation of the receptacles 8, which is performed as hereinbefore described, the contents of said receptacles 8 30 will be dumped into the uppermost chamber in the receptacles 17, while the ice will be ejected from the lowermost chambers in said receptacles onto the inclined platform 26 and will slide outwardly from the machine 35 in readiness to be taken by the operator and placed in an ice house.

Having thus described my invention, what I claim and desire by Letters Patent to secure is:

40 1. An ice making machine having, in combination a rotatable frustum-shaped primary receptacle for ice, a secondary receptacle for ice located below said primary re-

ceptacle and adapted to receive the contents of said primary receptacle when the latter 45 is rotated, and mechanism adapted to simultaneously rotate said receptacles, whereby the contents of said secondary receptacle may be ejected therefrom and the contents of said primary receptacle received thereby. 50

2. An ice making machine having, in combination, a rotatable frustum-shaped primary receptacle for ice, a secondary receptacle for ice located below said primary receptacle and having a plurality of chambers 55 therein, each of said chambers adapted to receive successively the contents of said primary receptacle when the latter is rotated and mechanism adapted to simultaneously rotate said receptacles, whereby the contents 60 of said secondary receptacle may be ejected therefrom and the contents of said primary receptacle received thereby.

3. An ice making machine having, in combination, a rotatable frustum-shaped primary receptacle for ice, a secondary receptacle for ice located below said primary receptacle and having a plurality of chambers 65 therein, each of said chambers adapted to receive successively the contents of said primary receptacle when the latter is rotated and mechanism adapted to simultaneously rotate said receptacles, whereby the contents 70 of said secondary receptacle may be ejected therefrom and the contents of said primary receptacle received thereby, said primary receptacle adapted to be rotated in one direction independently of said secondary receptacle. 75

In testimony whereof I have hereunto set 80 my hand in presence of two subscribing witnesses.

JOHN F. SOUTHER.
